UNITED STATES PATENT OFFICE.

GEORGE W. STREET, OF CHICAGO, ILLINOIS, AND JOHN S. WATTERS, OF BALTIMORE, MARYLAND.

BEDCLOTHING-CLAMP FOR BEDS.

SPECIFICATION forming part of Letters Patent No. 352,497, dated November 9, 1886.

Application filed January 11, 1886. Serial No. 188,229. (No model.)

To all whom it may concern:

Be it known that we, GEORGE W. STREET, of Chicago, county of Cook, and State of Illinois, and JOHN S. WATTERS, of Baltimore, in the State of Maryland, have jointly invented certain new and useful Improvements in Bed-clothing-Clamps for Beds; and we do hereby declare that the following is a full, clear, and exact description thereof, reference being had to the accompanying drawings, and to the letters of reference marked thereon, which form a part of this specification.

This invention relates to an improved clamping device to be applied to a suitably-located frame-piece upon a bedstead for the purpose of holding or securing in place the marginal parts of the bedclothing.

The invention consists in the matters hereinafter described, and pointed out in the appended claims.

The main features of the device herein shown as embodying our invention consist of a series of clamps, each comprising a stationary clamp-jaw attached to one of the frame-pieces of a woven-wire mattress, and a movable jaw pivotally connected with the stationary jaw, the several movable jaws being connected by a single rotating bar or rock-shaft, whereby all of the jaws may be actuated at once in opening and closing them. Suitable means are provided, in connection with the shaft, for actuating the latter in opening and closing the jaws, as fully hereinafter set forth.

The invention may be more readily understood by reference to the accompanying drawings, in which—

Figure 1 is a side or exterior elevation of the frame of a woven-wire mattress provided with a series of clamps, and a rock-shaft for actuating the clamps, constructed in accordance with our invention. Fig. 2 is a transverse section of the same, taken upon line $x-x$ of Fig. 1. Fig. 3 is a detail elevation of the ratchet-wheel upon the end of the rock-shaft for holding the jaws closed, shown in Fig. 1. Fig. 4 is a detail perspective view of one of the clamps shown in Fig. 1. Fig. 5 is a detail view of a clamp illustrating another means for holding the movable clamp-jaw in its closed position.

In the said drawings, A indicates the frame-piece to which the clamping devices are at-

tached, said frame-piece in the particular construction illustrated being the end or foot cross-bar of the frame of a woven-wire mattress.

55

B indicates, as a whole, the clamps, each of which consists of a stationary jaw, B', attached to the frame-piece A, and a movable jaw, B², which is pivotally connected with the stationary jaw, said jaws being arranged with their free ends upward and in convenient position to engage the marginal parts of the bedclothing C, herein shown as extended over a mattress, D, which rests upon the woven-wire fabric A', attached to the frame-piece A.

65

The clamp-jaws B' B² are preferably curved outwardly or spread apart from each other in their portions below their upper end portions which form the clamps proper, so as to afford free or open spaces to receive the marginal parts of the bedclothing which may be drawn downwardly into the clamps. The stationary jaw B' is preferably secured to the frame-piece A by means of a plate or flange, B³, thereon, extending beneath the frame-piece A, and is secured to the latter by screws, as shown, or otherwise. Said stationary jaw also is preferably cast with bearings B⁴ for the rock-shaft E, which is arranged to pass through the bearings of the several clamps, and is rigidly connected with the movable jaws B² of the latter to sustain and move the said several jaws.

75

As a simple and cheap construction in the shaft E, said shaft is, as herein shown, made square in cross-section and of uniform size throughout its entire length, and is fitted to correspondingly-shaped apertures in the hubs b of the movable clamp-jaws B², suitable cylindrical bearing-surfaces being formed upon said shaft by means of sleeves E', made cylindrical upon their outer surfaces and of proper size to enter the bearings B⁴, and provided with square apertures, whereby they may be slipped over the rod. Said sleeves, as shown, are provided with set-screws e, to hold them from endwise movement upon the rod; but they may be otherwise secured thereon in practice, as is found convenient or desirable.

90

One means applied to the rock-shaft E for actuating the clamp-jaws B² and holding the latter closed is shown in Figs. 1 and 3. In these figures, F indicates a ratchet-wheel secured upon the end of the shaft, and provided

with a handle or lever, F', whereby said wheel and the shaft may be conveniently turned. Upon the side rail, A², of the mattress-frame adjacent to the said wheel is pivoted a pawl, 5 f, which is held in engagement with the wheel F by means of a spring, f', the teeth upon the wheel being so inclined as to allow the latter to be freely rotated in a direction to close the jaws. In the operation of this device the pawl f is released by hand from the ratchet-wheel in opening the jaws, and the latter then turned by means of the handle F' until the clamp-jaws are opened sufficient to conveniently receive the marginal part of the bed-clothing. In closing the jaws the ratchet-wheel is turned in an opposite direction until the clothing is tightly clamped, when the pawl f, by its engagement with the ratchet-teeth, will prevent any backward movement of the 20 movable clamp-jaws.

In the particular construction illustrated in Fig. 1 the rock-shaft E is shown as provided near its ends with additional bearings e', secured to the ends of the rails A² A², the said 25 shaft being provided with sleeves E', similar to those before described, upon its part engaged with the said bearings e'.

For the general purposes of our invention it is not necessary that the several movable 30 clamp-jaws should be connected with and actuated by a single shaft, although this construction is, for several reasons, a desirable one, and is herein specifically claimed as a preferred way of carrying out our invention. It is to be 35 understood, furthermore, that the movable jaws may be held in position for clamping the clothing by other means than the ratchet-wheel and pawl shown—as, for instance, the construction shown in Fig. 5 may be used, in 40 which a leaf-spring, G, is attached to the movable jaw and adapted to press at its free end against the flange B³ in such manner as to normally hold the jaws closed. In the use of a device constructed in this manner the several jaws may be secured to a single shaft, so 45 that all may be actuated together in the manner before described, in which case the shaft may have upon its end a lever, as indicated at H, Fig. 5; or the movable jaws may be independent of each other. When this latter 50 construction is used, the jaws will be moved separately by the hand for the insertion of the bedclothing between them.

A clamp or a series of clamps such as above 55 set forth may obviously be applied to a suitably-located stationary part or frame-piece of the bedstead proper, as well as to the frame-piece of a woven-wire mattress, as herein illustrated. In some instances, also, the clamps 60 will be attached to frame-pieces of the mattress, which also form the frame-pieces of the bed, as is the case, for instance, in a familiar form of cot or hospital-bed, in which suitable legs are attached directly to the frame of a woven-wire mattress, such as is herein shown.

In Fig. 2 is shown a portion of a foot-board, I, in the position which it will usually occupy

with relation to the clamp when the latter is used upon a bedstead having a foot-board. The movable jaw B² (shown in Fig. 2) is shaped 70 at its outer part to permit the greatest possible movement in the upper end of said jaw when a foot-board is present, the said jaw being adapted to swing outwardly until its end is brought into contact with the foot-board, 75 whereby the edges of the bedclothing may be readily inserted between the jaws preparatory to closing the clamps.

It is to be understood that the appended claims cover the several parts of devices there-in set forth, when said several parts or devices are constructed in form to obtain either, any, or all of the advantages or benefits obtained by said parts or devices in the particular form thereof herein illustrated and above described. 85

We claim as our invention—

1. The combination, with a bed-frame, of a series of clamps comprising stationary and movable jaws, and a bar or rock-shaft, E, engaging the several movable jaws for actuating 90 the latter, substantially as described.

2. The combination, with a bed-frame, of a series of clamps comprising stationary and movable jaws, and a rock-shaft supporting the said movable jaws, the stationary jaws being 95 provided with bearings for the rock-shaft, substantially as described.

3. The combination, with a bed-frame and a series of stationary and movable jaws, of a rock-shaft, E, engaged with and supporting 100 the said movable jaws, and suitable bearings for the rock-shaft upon the frame, said rock-shaft being made of square iron and provided with sleeves E', made cylindric upon their outer surfaces to engage the shaft-bearings, 105 substantially as described.

4. The combination, with the stationary and movable clamp-jaws, and the rock-shaft E, engaging the movable jaws, of a ratchet-wheel, F, upon the said shaft, provided with a handle, 110 F', and a pawl, f, engaging said ratchet-wheel, substantially as described.

5. The combination, with stationary and movable jaws, of a rock-shaft, E, made square throughout its entire length, and engaging 115 square apertures in the movable jaws, and sleeves E', fitted upon the rock-shaft and made cylindric on their outer surfaces, set-screws holding said sleeves from end movement upon the shaft, and suitable bearings for the shaft 120 engaging said sleeves, substantially as described.

In testimony that we claim the foregoing as our joint invention we affix our signatures in presence of two witnesses.
